CLAIM

The ornamental design for clothespin, as shown and described.

DESCRIPTION

FIG. 1 is a front elevational view of a clothespin embodying our new design and showing the clothespin in a closed position;

FIG. 2 is a front elevational view of a clothespin embodying our new design and showing the clothespin in an opened position;

FIG. 3 is a top plan view of the design;

FIG. 4 is a bottom plan view of the upper member of the clothespin of FIGS. 1 and 2;

FIG. 5 is a top plan view of the lower member of the clothespin of FIGS. 1 and 2;

FIG. 6 is a bottom plan view of the design; and,

FIG. 7 is a cross sectional view taken on line 7—7 of FIG. 3.

The broken line showing of a spring is for illustrative purposes only and forms no part of the claimed design.
